UNITED STATES PATENT OFFICE.

EDWARD P. BULLARD, OF BRIDGEPORT, CONNECTICUT, ASSIGNOR TO THE BULLARD MACHINE TOOL COMPANY, OF BRIDGEPORT, CONNECTICUT, A CORPORATION OF CONNECTICUT.

CHUCK-JAW.

SPECIFICATION forming part of Letters Patent No. 729,727, dated June 2, 1903.

Application filed December 9, 1902. Serial No. 134,531. (No model.)

To all whom it may concern:

Be it known that I, EDWARD P. BULLARD, a citizen of the United States, and a resident of Bridgeport, in the county of Fairfield and State of Connecticut, have invented certain new and useful Improvements in Chuck-Jaws, of which the following is a specification.

This invention relates to new and useful improvements in chuck-jaws such as are extensively used on drills, lathes, boring-mills, &c.

It is the object of my invention to improve upon jaws of the above class in several important particulars, the first of which is to provide a jaw which will grip and hold an article firmer than those now in use; second, to construct said jaw in a way that the entire load will not come entirely against the clamping-screw, but may be deflected against the ways in which the jaw is mounted; third, to so arrange the device that the adjusting-screw will not set up against the jaw and project therefrom, but will be arranged to one side below the plane of the jaw and at an angle thereto other than a right angle to the line of movement of the jaw, thus making the article more compact and requiring less space upon the table, all of which are very important features.

With the above objects in view my invention resides and consists in the novel construction and arrangement of parts shown upon the accompanying sheet of drawings, forming a part of this specification, upon which similar letters of reference denote like or corresponding parts throughout the several figures, and of which—

Figure 1 shows a perspective view of a boring-mill table detached with a series of four of my improved clamping-jaws attached thereto and ready for use. Fig. 2 is a plan view of my improved clamping-jaw detached. Fig. 3 is a longitudinal vertical section taken on line 3-3 of Fig. 2 and is designed to illustrate the connection between the screw and jaw. Fig. 4 is an end view as seen from the left of Fig. 2. Fig. 5 is a similar end view of a smaller or single-way jaw.

Referring in detail to the reference characters marked upon the drawings, A represents a rotary table, such as is commonly

found on various kinds of machine-tools, particularly drills, lathes, boring-mills, &c. This table, as is usual, is provided with a series of radially-arranged grooves B, in which various forms of tools are designed to be secured, and are especially adapted for gripping-jaws such as my invention comprises. The majority of clamping-jaws of this class now found upon the market are provided with a screw which sets out from the rear end in a manner to operate the jaw as desired. This form of device is objectionable for two reasons, one being the fact that it necessarily sets up high above the table and likewise projects out far from the outer end, thus being objectionable, for the reason that it is very much in the way. Further, such a construction is weak and quickly gives way under the severe usage that it gets.

My invention may be attached to any of the usual forms of machine-tables and requires no special construction other than that usually found. It comprises an attachable portable base C to fit upon the face of machine-tables and is provided with one or more ways D to engage the before-mentioned grooves B of said table. This base is provided with bolts F for its attachment to the table, which bolts pass through the holes E of said bed and engage the shoulders of the grooves B in the usual way. This base is further provided with a way G, having longitudinal ribs H in its side walls, the whole adapted to receive the jaw I, which is surfaced to fit said ways and ribs in a manner to allow the jaw to slide longitudinally therein, but at the same time retain it in engagement with the adjusting-screw, as will later be explained. The jaw proper contains the usual gripping-surfaces J and is further provided with a diagonally-arranged toothed bottom surface K, as will be seen in dotted lines in Fig. 2. At a right angle to the face of these teeth and diagonally through the lower portion of the base is arranged a bore L, the ends of which are inclosed by caps M, the latter also forming a bearing for a diagonally-arranged adjusting-screw N, the threads of which engage the toothed rack on the under side of the jaw in a manner to operate

and retain the same, as will be seen. The two exposed outer ends of this adjusting-screw are provided with a square head O to receive a wrench or other tool for operating 5 the screw to move the jaw forward or backward. Owing to the diagonal arrangement of the screw, the operating ends of the latter are brought to one side of the base and can be more conveniently operated from either 10 end, and by reason of the screw being located beneath the jaw said ends are likewise brought down close to the face of the table, so that it is practically out of the way, yet 15 convenient for operating. Owing to the great number of threads in the screw and teeth in the jaw for engaging the screw, a very strong and reliable engagement is had between the parts, thus being equal to any strain that is 20 brought to bear.

Having thus described my invention, what 25 I claim, and desire to secure by Letters Patent, is—

1. In a device of the class described, the combination with a portable base having means 25 of attachment to a table, of a jaw mounted

therein and containing diagonal teeth on its under side, a bore arranged diagonally with reference to the line of movement of jaw through the base, an adjusting-screw mounted in said bore in engagement with the teeth of 30 the jaw for operating the latter, said screw extending through the base with exposed engaging heads on either end.

2. In a device of the class described, the combination with a portable base, of means for 35 its attachment to a machine, a jaw mounted in said base bearing teeth on its under side, a bore through the base, bearing-caps inclosing either end of said bore, a screw mounted in said bearing-caps to engage the jaw, and 40 heads on either end of the screw for adjusting the same.

Signed at Bridgeport, in the county of Fairfield and State of Connecticut, this 1st day of December, A. D. 1902.

EDWARD P. BULLARD.
